LOUIS N. D. WILLIAMS, OF OGONTZ, PENNSYLVANIA, ASSIGNOR TO SCOTT & WILLIAMS, INCORPORATED, OF NEW YORK, N. Y., A CORPORATION OF MASSACHUSETTS

NEEDLE ARRESTING MEANS FOR KNITTING MACHINES

Application filed January 14, 1929. Serial No. 332,494.

This invention relates to arresting means useful with knitting machines to prevent movement of the needles incidental to transfer operations.

- 5 The manufacture of certain classes of knit wares, for example seamless stockings and the like, entails transfer operations wherein a transfer device with points—ordinarily known as a point ring—is employed to receive 10 the fabric loop for loop from the producing machine to enable placement in other machines for furtherance or completion of the work. Bad or poor transfers often result in 15 the performance of these operations due to lifting of the needles and detention of clinging fabric loops as the point ring is withdrawn from the knitting machine with consequent strippage of such fabric loops, as well as neighboring ones, from the points of 20 said ring.

My present invention is directed toward overcoming the recited difficulty through provision of arresting means with a stop element capable of projection into the path of the 25 needles of the knitting machine to prevent them from moving as the point ring is lifted off.

The use of the needle arresting means herein featured is particularly advantageous with 30 automatic transfer mechanism of the kind disclosed in my copending application Serial No. 72,483, filed December 1, 1925, the same having, subsequent to the filing of this case, matured as Patent No. 1,715,399, dated July 35 4, 1929, and may be regarded as an alternative to the needle arresting means shown and described in still another application Serial No. 332,493 filed concurrently herewith. In this connection, as in the previous instance, 40 I aim to provide for automatic operation of the needle arresting means incidental to manipulation of the point ring in transferring by the mechanism provided for that purpose.

In the drawings, Fig. I shows a fragmentary elevation of a circular knitting machine with automatic transfer mechanism corresponding generally in design to that set forth 45 in the co-pending application, supra, but em-

bodying the needle arresting means of the present invention in one practical form.

Fig. II is a fragmentary sectional view through the knitting head of the machine with the point ring lowered in readiness to 55 receive the fabric from the needles.

Figs. III and IV are views, similar to Fig. II, showing successive steps in the transfer operation.

Fig. V is a detail plan section, taken as indicated by the arrows V—V in Fig. I, showing the needle arresting means in the normal retracted or inactive position.

Fig. VI is a view, similar to Fig. V, taken as indicated by the arrows VI—VI in Fig. 60 II, showing the needle arresting means in the advanced or active position.

Fig. VII is a detail sectional view showing means for preventing accidental rotation of the needle cylinder of the knitting machine 70 during fabric transfer.

Figs. VIII, IX and X, are fragmentary sectional views showing an alternative form of my invention.

With more detailed reference to the drawings, C designates the cylinder of the knitting machine which is provided with the usual longitudinal surface grooves to support and guide the latch needles N. As shown in Figs. II—IV, the needle cylinder C extends down through an opening in the bed plate 10 of the machine, and at its lower end is secured by screws to a bevel gear 11 which is rotatable in a circular recess of a supplemental bed plate 12. This supplemental bed plate 12 75 is suitably supported in concentric relation to the main bed plate 10 and spaced from the latter by a vertical interval of sufficient depth to conveniently accommodate the needle arresting means which will be described later. 80 With the needles N cooperate sinkers S which are supported in a head 13 at the top of a vertically shiftable sleeve 14 that extends axially down through the needle cylinder C. The sleeve 14 is splined to the cylinder C at 85 15 so as to normally rotate therewith, but connected with capacity for independent rotation to the fabric receiver 16 of the machine, said receiver being slidably engaged 90 in a depending boss 17 of the supplemental 95 100

bed plate 12. The machine is otherwise of usual construction with the shell 18 for the needle actuating cams secured to or forming a part of the main bed plate 10, and provided with suitable means, not shown, for automatically levelling the needles N at the completion of the knitting cycle in this case after a complete stocking blank has been knit.

The automatic transfer mechanism herein delineated includes a carrier arm 20, which, at its free end, affords a cylindrical holder 21 for a point ring R. This carrier arm 20 is secured to a shaft 22 with journal support in a fixed bracket 23 upstanding from the main bed plate 10 alongside the needle cylinder C, for capacity to swing, from the retracted or loading position of Fig. I, to axial position over said needle cylinder with the points P of the ring R in registry with the needles N (previously leveled) as in Fig. II. After placement of the point ring R in the manner just explained, a yoke lever 24 with fulcrum connection at 25 on the carrier arm 20 depresses said ring, as shown in Fig. III, so that the points P thereof enter the loops on the needles N in readiness for transfer of the fabric. The final step in the transfer operation is effected, as shown in Fig. IV, through raising of the sleeve 14 that supports the sinker head 13, whereby the fabric loops are displaced from the needles N for retainment by the points P of the ring R, the latter being at the same time restored to its original position in the holder 21 of the carrier arm 20. The various steps in the manipulation of the point ring R during the transfer operation are controlled by a timing mechanism which is comprehensively designated by the numeral 26. As shown in Fig. I this timing mechanism comprises a drum 27 which is adapted to be intermittently picked by a ratchet pawl 28 receiving oscillatory motion through the medium of a link 29 from a suitable moving part (not shown) of the knitting machine. From Fig. I it will be further observed that near its upper end the drum 27 has a circumferential cam groove 30 to engage a roller 31 on the end of an arm 32 which is secured to a shaft 33 with journal bearing in a drop bracket 35 bolted to the supplemental bed plate 12. Also secured to the shaft 33 is a toothed sector 36 which meshes with a pinion 37 fast on the fulcrum shaft 22 of the carrier arm 20. Thus, with each rotation of the drum 27, the carrier arm 20 is automatically swung inward to place the point ring R over the needle cylinder C, and, after the transfer operation, again retracted to the normal position of Fig. I, to withdraw said point ring—together with the transferred fabric—from the needles N of the machine. The drum 27 has still another circumferential cam groove 38 to engage a stud 39 on an arm 40 that is secured to a second shaft 41 jour-

nalled in the drop bracket 35, and, through these interposed elements, serves to impart movement to a finger 42 in engagement with a notched lug 43 on the fabric receiver 16. The fabric receiver 16 is accordingly shifted upward to the end that the sinker head 13 is raised during transfer in the manner already explained. The drum 27 of the timing mechanism 26 further serves to automatically actuate a push rod 45 for engaging the tail 20a of the carrier arm 20 to hold the latter against displacement when down; and moreover controls the movement of a vertical hook rod 46 which is arranged to engage a pin 47 on the yoke lever 24 in effecting depression of the point ring R within the holder 21 of the carrier arm 20, for a purpose also pointed out hereinbefore. In addition, the timing mechanism 26 governs, through a pivoted finger 48, a spring pressed locking bolt 49 whereby the needle cylinder C is secured against accidental rotation during the transfer period, said bolt passing down through the bed plates 10, 12 of the machine and engaging the bevel gear 11, as illustrated in Fig. VII. I also show in Figs. II, III and IV, an ejector rod 50, which, at the proper time, thrusts the stocking blank upwardly through the needle cylinder C, the point ring R, and the axial tubular extension 51 of the holder on the carrier arm 20 to lodge said fabric between opposing spring sustained retaining brushes 52 Fig. I that extend crosswise of the open end of said extension. Any suitable means may be employed to operate this ejector rod 50, all as shown and explained in the patent and co-pending application above referred to.

Coming now to the form of my needle arresting means shown in Figs. I-VII, as embodied in an organization such as described up to this point, it will be seen that the same comprises a number of segmental members 55 (Figs. V and VI) which are supported, with capacity for sliding movement, in radial slots of an annulus 56 secured by means of screws 57 to the lower face of the main bed plate 10 in concentric relation to the needle cylinder C. From the segmental members 55 depend studs 58 (Figs. II-VI) which engage angularly arranged slots 59 in a cam ring 60 which is removably retained in the assemblage, by under-reaching angle clips 61 fastened by screws 62 to the periphery of the annulus 56 at spaced points circumferentially. Through shifting the cam ring 60 clockwise, or in the direction of the arrow in Fig. V, the segmental members 55 are therefore moved inwards simultaneously, their arcuate extent being such that when contact is finally made with the needle cylinder C, they collectively form a continuous circular stop element in the path of the butts 63a of supplemental jacks 63 which occupy the lower portions of the needle grooves in

said cylinder. As shown at 64 in Figs. II-IV, the supplemental jacks 63 have hooked engagement with the needles N immediately below the usual butts of the latter. For actuation of the needle arresting means I rely on a link connection 66 with the gear sector 36. Accordingly, as the sector 36 is operated to bring about lowering of the point ring R onto the needle cylinder C, the segmental members 55 of the needle arresting means are moved into the active position of Figs. II, IV and VI, to hold the needles N against lifting during the subsequent steps of the transfer operation. At the completion of the transfer operation and during reverse actuation of the gear sector 36 to withdraw the point ring R, the segmental members 55 are in a like manner retracted, to the inactive position of Fig. V, so that the normal operation of the machine in knitting a new stocking blank may proceed without interference.

Figs. VIII, IX and X, show an alternative form of my invention in which the use of supplemental jacks is dispensed with. In this instance I permanently secure to the top of the needle cylinder C' a collar 70. On this collar 70 is mounted a circular plate 71 which is held against displacement through lap of its depending circumferential flange 71a over the outer periphery of said collar. The inner edge of the circular plate 71 has notches 71b which correspond in number to, and which are normally aligned with the grooves of the cylinder C' as shown in Fig. VIII, for free passage of the needle N' incidental to knitting. However, through a slight shift of the circular plate 71 equal to half the distance between notches 71b, the tongues 71c intervening said notches are brought over the upper ends of the needle grooves in the cylinder C' and thus projected laterally into the path of shoulders 72 on the shanks of the needles N'. Such shifting of the plate 71 is limited through cooperation of studs 73 (of which but one is shown in Figs. VIII and X) let into the edge of the collar 70, with slots 74 in the flange 71a of said plate. A helical spring 75 in tension between a fixed anchorage 76 on the collar 70 and an eye 77 of the flange 71a acts to maintain the plate 71 in the normal position above referred to. Any suitable means may be employed in coordination with the timing means 26 of the transfer mechanism to actuate the plate 71 after the cylinder C is locked in position, and before the lift of the sleeve 14', to dislodge the point ring R for example, a lever 78 which is rockable about a fixed pivot 79 and equipped with a spring tongue 80 to engage a depending lug 81 of the plate 71, all as depicted in Figs. VIII and X.

Although I have herein shown and described the needle arresting means of my invention in connection with knitting machines embodying automatic transfer mechanism, it

can obviously be used with equal advantages on knitting machines not so equipped where the point ring is applied and withdrawn by hand in effecting fabric transfers.

Having thus described my invention, I claim:

1. Needle arresting means for knitting machines involving transfer mechanism comprising a stop element projectable laterally into the path of the needles to prevent upward movement of the latter incidental to loop transferring operations, and mechanism to actuate the stop element concurrently with withdrawal of fabric from the needles by the transfer device.

2. Needle arresting means for knitting machines including transfer mechanism comprising a stop element projectable into the path of shoulders on the needles to prevent upward movement of the latter incidental to loop transferring operations, and cam controlled mechanism to actuate the stop element simultaneously with raising of the transfer device to withdraw fabric from the needles.

3. Needle arresting means for knitting machines including transfer mechanism comprising a stop element projectable laterally into the path of the needles to prevent upward movement of the latter incidental to loop transferring operations, and mechanism coordinated with the transfer carrier shaft to automatically operate the stop element through rotative action simultaneously with the raising of the transfer device to withdraw fabric from the needles.

4. Needle arresting means for knitting machines including transfer mechanism comprising a stop element projectable into the path of supplemental lateral shoulders on the needles at a level spaced from that of the usual needle butts to prevent upward movement of the needles incidental to loop transferring operations, and cam controlled mechanism to automatically actuate the stop element concurrently with withdrawal of fabric by the transfer device from the needles.

5. Needle arresting means for circular knitting machines including transfer mechanism comprising a number of segmental members capable of radial projection to collectively constitute a continuous annular stop element in the path of the needles to prevent upward movement of the latter incidental to loop transferring operations, and cam controlled gear and link mechanism to automatically actuate the segmental members aforesaid as the transfer device moves away from active relation with said needles in withdrawing fabric therefrom.

6. Needle arresting means for circular knitting machines including transfer mechanism comprising a number of segmental members capable of radial projection to col-

lectively constitute a continuous annular stop element in the path of the needles to prevent upward movement of the latter incidental to loop transferring operations, supporting means to guide the segmental members for movement as aforesaid, and cam controlled gear and link mechanism actuatable to move all of the segmental members into the active position simultaneously with withdrawal of the fabric from the needles by the transfer mechanism.

7. Needle arresting means for circular knitting machines including transfer mechanism comprising a number of segmental members capable of radial projection to collectively constitute a continuous annular stop element in the path of the needles to prevent upward movement of the latter incidental to loop transferring operations, means to support and guide the segmental members for movement as aforesaid, a concentric plate with angularly arranged cam notches to engage projections on said segmental members, and mechanism including a gear sector and link for rotatively shifting said plate to simultaneously move all of the segmental members into active position concurrently with withdrawal of fabric from the needles by the transfer mechanism.

8. Needle arresting means for circular knitting machines including transfer mechanism comprising jacks individually associated with the needles of the knitting machine and affording supplemental butts accessible beneath the bed plate surrounding the needle cylinder, a number of segmental members capable of radial projection to collectively constitute a continuous annular stop element in the path of the jack butts to prevent upward movement of the needles incidental to loop transferring operations, and cam actuated mechanism including a gear sector and link effective to simultaneously move all of the segments into active position incidental to withdrawal of fabric from the needles by the transfer mechanism.

9. In a knitting machine embodying a series of needles and a movable carrier means for applying a transfer device to register its points with the needles; needle arresting means comprising a series of stop elements capable of projection laterally into the path of the needles to prevent upward movement of said needles incidental to loop transfer, and coordinative means between the stop elements of the needle arresting means whereby the latter is actuated concurrently with elevation of the carrier means to withdraw fabric from the needles by the transfer device.

10. In a knitting machine with a series of needles and a movable carrier means for applying a transfer device to register its points with the needles in readiness to receive fabric from the needles; needle arresting means

comprising a stop element capable of projection laterally into the path of the needles to prevent upward movement of said needles under drag of the fabric incidental to transfer of the latter to the points of the transfer device, and mechanism coordinating the needle arresting means with the carrier means aforesaid whereby the stop element is advanced into active position concurrently with application of the transfer device to the needles and retracted upon withdrawal of said transfer device at the completion of the loop transfer.

11. In a knitting machine embodying a series of needles, a pivoted carrier for applying a transfer device to register its points with the needles in readiness to receive fabric from the needles, and a gear sector to swing the carrier; needle arresting means comprising a stop element capable of projection laterally into the path of the needles to prevent upward movement of the needles under drag of the fabric loops incidental to transfer of the latter to the points of the transfer device, and mechanism coordinating the needle arresting means with the gear sector aforesaid whereby the stop element is advanced into active position concurrently with application of the transfer device to the needles and retracted upon withdrawal of said transfer device at the completion of the transfer operation.

12. In a knitting machine embodying a series of needles and automatic transfer mechanism including a pivoted carrier for applying a transfer device to register its points with the needles in readiness to receive fabric from the needles, and timing means for controlling movement of said carrier; needle arresting means comprising a stop element capable of projection laterally into the path of the needles to prevent upward movement of the needles under drag of the fabric loops incidental to transfer of the latter to the points of the transfer device, and means governed by the timing means of the automatic mechanism aforesaid to actuate the stop element concurrently with application and removal of the transfer device relative to the needles.

13. In a circular knitting machine embodying a cylinder with needles and a movable carrier for applying a transfer ring to register its points with the needles in readiness to receive fabric from said needles; needle arresting means comprising a number of segmental members capable of radial projection to collectively constitute a continuous annular stop element in the path of the needles thereby to prevent upward movement of said needles under drag of the fabric loops incidental to transfer of the latter to the points of the transfer device, actuating means for the segmental members of the needle arresting means, and means coordinat-

ing said actuating means with the ring carrier aforesaid whereby the segmental members are simultaneously advanced into active position with application of the point ring to
5 the needles and retracted upon withdrawal of said ring at the completion of the transfer operation.

14. In a circular knitting machine embodying a cylinder with needles, automatic
10 transfer mechanism including a movable carrier for applying a transfer ring to register its points with the needles in readiness to receive the fabric from said needles, and timing means for controlling operation of the
15 carrier; needle arresting means comprising a number of segmental members capable of radial projection to collectively constitute a continuous annular stop element in the path of the needles thereby to prevent upward movement of said needles under drag of the fabric loops incidental to transfer of the latter to the points of the transfer device, and actuating means for the segmental members of the needle arresting means governed by the timing means of the automatic transfer mechanism aforesaid so that the segmental members are simultaneously advanced in active position concurrently with movement of the carrier to apply the point
20 ring to the needles.
25

In testimony whereof, I have hereunto signed my name at Philadelphia, Pennsylvania, this 26th day of December, 1928.

LOUIS N. D. WILLIAMS.
